VALVE

Herbert Hansen, Oak Park, Ill., assignor of one-half to Refrigerating Specialties Co., Chicago, Ill., a corporation of Illinois

Application February 12, 1938, Serial No. 190,147

4 Claims. (Cl. 251—141)

The invention relates to valves.

One object of the invention is to provide an improved globe-type of valve with means for directing the fluid from the valve-seat to the discharge side of the casing so that the turbulence caused by the change of direction and the retardance to the fluid will be reduced.

Another object of the invention is to embody this flow-directional means in a structure which 10 is integral with the valve-seat and removable therewith.

Other objects of the invention will appear from the detailed description.

The invention consists in the several novel 15 features which are hereinafter set forth and are more particularly defined by claims at the conclusion hereof.

In the drawing:

Fig. 1 is a central longitudinal section of a 20 valve embodying the invention. Fig. 2 is a transverse section through the integral valve-seat and flow-directional means. Fig. 3 is a section on line 3—3 of Fig. 2.

The invention is exemplified in a valve comprising a casing which consists of a globular central body 5, a screw-threaded tubular portion 6 at one side of body 5 to which an inlet-pipe may be connected by a union-coupling 7, a tubular extension 8 at the opposite side and coaxial 25 with the extension 6, to which an outlet pipe may be connected by a union-coupling 9, a transverse central wall 10 and inclined walls 11 and 12 between wall 10 and the body 5 at the inlet and outlet sides of the casing, respectively. Extensions 6 and 8 and walls 10, 11 and 12 are integral 30 with the body 5. The transverse wall 10 has a cylindrical opening 13 to receive an annular valve-seat 14 which is provided with an outwardly extending flange 15 for engaging a packing-ring 16 held in an annular groove on the underside of cross-wall 10 and around opening 13 to form a fluid-tight joint between the seat and wall 10. The seat 14 is provided with an integral upwardly extending curved wall 17 which terminates at its upper end in a tubular 35 internally screw-threaded extension 18. A sleeve 19 is provided with a shoulder 20 for engaging a packing-ring 21 which fits on the top wall 22 of the casing, has an extension 23 which passes into the body 5 through an opening 24 in wall 22 and an external screw-thread at its lower 40 end interfitting with the internal thread on the tubular extension 18 which is integral with the wall 17 and valve-seat 14. Sleeve 19 is rotatable 45 in the casing so that, by means of the screw-

threaded connection between extensions 23 and 18, flange 15 of the valve-seat 14 can be jammed toward the cross-wall 10 to form a fluid-tight joint between the valve-seat and said wall. The curved wall 17 approximates 180° or slightly 5 more, extends around the sides of the valve-seat and terminates in an opening at the outlet side. The upper portion of wall 17 is formed on an arc, so the fluid will be deflected to approximately a right angle from its direction 10 when it leaves the seat. The curvatures of wall 17 are such as to direct the flow of fluid passing upwardly from an upward direction at the valve-seat laterally and slightly downwardly toward the discharge side of the casing. This wall 15 directs and deflects fluid from the seat in a gradual curve from the valve-seat to the discharge side of the casing, outwardly of wall 12, and into the outlet extension 8. This directional flow means reduces the turbulence caused by the 20 necessary change of direction of the flow between the valve-seat and the outlet extension, reduces the retardance of the flow of fluid from the seat to said outlet so there will be less drop in pressure than would otherwise occur. 25

A valve-member 26 is adapted to close against the underside of valve-seat 14 and is movable with a slideable plunger 27. Valve-member 26 may be of suitable material to form a tight joint with the valve-seat, is confined in an annular flange on the upper end of the plunger 27 and is secured in the plunger by a retaining screw 28 which is adapted to clamp the member 26 against a horizontal shoulder on the plunger. Plunger 27 is slidably mounted in a cap 29 which 30 is screw-threaded into and fits against the lower side of a tubular extension 30 on the lower end of casing 5. A spring 31, located in cap 29 and the socket in plunger 27, is provided to normally hold the valve-member 26 firmly against the seat 35 14 to close the valve. The valve-seat 14 and its directional flow walls and extension 18 are removable from the casing when the cap 29 is removed, the opening in extension 30 for said cap being of sufficient diameter to permit the 40 valve-seat and wall 17 to pass therethrough during insertion and removal of the valve-seat. 45

A stem 32 is adapted to abut against the top of screw 28 to force valve-member 26 and plunger 27 downwardly against the force of spring 31 50 to open the valve. Any suitable means may be provided for operating the stem 32, such as a hand-wheel 33 secured to the upper end of stem 32 and screw-threads 34 on said stem which has a threaded engagement with the sleeve 19, so 55

that when the wheel is turned stem 32 may be shifted to open or close the valve. A packing-box 35 is provided to form a water-tight seal between stem 32 and sleeve 19.

5 In operation, when the valve-member 26 is open, the fluid passing upwardly between said member and the valve-seat will be gradually deflected in a curved path by the curvature of wall 17, laterally and downwardly over wall 12 and 10 towards and into the outlet extension 8 of the casing. By controlling the direction of flow in this manner the turbulence produced by the 15 directional change will be reduced with a reduction in the retardance to the flow of the fluid and less drop in pressure than would result without said wall. The directional flow means is integral with the valve-seat so it can be assembled into the casing with the valve-seat and removed 20 from the casing with the seat. The cap in the bottom of the casing permits the valve-seat and flow directional means to be readily removed from the casing. The connection between the sleeve 19 and the valve-seat and flow means serves to secure the valve-seat in the cross-wall 25 with a fluid-tight joint.

The invention is not to be understood as restricted to the details set forth, since these may be modified within the scope of the appended claims without departing from the spirit and 30 scope of the invention.

Having thus described the invention, what I claim as new and desire to secure by Letters Patent is:

35 1. A valve comprising in combination a casing provided with a fluid inlet and an outlet, a cross-wall in the casing disposed between the inlet and the outlet and having an opening therein, an annular valve-seat fitting in said opening and having a flange at, and in engagement with, the inlet side of said cross-wall, a curved directional flow controlling wall connected rigidly to the seat and extending from the latter into the outlet side of the casing in such manner as to direct the fluid from the seat through the outlet, means 40 extending between the curved wall and the adjacent portion of the casing for drawing the seat into clamped engagement with the cross-wall, a valve member for engaging the seat and controlling the flow of fluid from the inlet through the 45 opening in the cross-wall opening into the outlet, and means for shifting the valve member.

50 2. A valve comprising in a horizontally elongated open ended combination casing having an internally threaded centrally disposed hole in its top and provided with a cross-wall serving to form a fluid inlet compartment in the lower portion of the casing and a fluid outlet compartment in the upper portion of said casing and having an opening therein between the two compartments, an annular valve-seat fitting in said 55 opening and having a flange at, and in engagement with, the inlet compartment side of said cross-wall, a directional flow controlling wall in the outlet compartment and with an internally threaded hole in opposed relation to the first 60 mentioned hole, connected rigidly to the seat and shaped to direct the fluid at an angle from the seat and through the outlet compartment and adjoining open end of the casing, a sleeve with externally threaded ends, having one end thereof 65 fitting in the hole in the top of the casing and its other end fitting in the hole in the flow controlling wall and serving to draw the seat into clamped relation with the cross-wall, a valve- 70

member for closing the seat, and means for shifting said valve-member comprising a stem extending through said sleeve.

3. A valve comprising in combination a horizontally elongated open ended casing having a 5 centrally disposed hole in its bottom and provided with a substantially horizontal cross-wall serving to form a fluid inlet compartment in the lower portion of the casing and a fluid outlet compartment in the upper portion of said casing 10 and embodying a circular opening therethrough for permitting fluid to flow from the inlet compartment to the outlet compartment, a cap for closing the hole in the casing bottom secured removably to the casing, an annular valve seat in said opening and with a flange at, and in engagement with, the inlet compartment side of, the cross-wall, having means associated therewith for releasably holding it in clamped relation with said cross-wall and adapted upon release of said 15 means and removal of the cap to be removed from the casing through the aforesaid hole, a directional flow controlling wall in rigidly connected relation with the seat disposed normally in the outlet compartment and adapted to direct the fluid through the last mentioned compartment and the adjoining open end of the casing and also to be removed from the casing with the seat, a valve member for engaging the seat and closing the opening against the passage 20 of fluid from the inlet compartment to the outlet compartment via said flow controlling wall, and means for shifting the valve member.

4. A valve comprising in combination a horizontally elongated open ended casing having a 35 centrally disposed hole in its bottom and provided with a substantially horizontal cross-wall serving to form a fluid inlet compartment in the lower portion of the casing and a fluid outlet compartment in the upper portion of said casing 40 and embodying a circular opening therethrough for permitting fluid to flow from the inlet compartment to the outlet compartment, a cap for closing the hole in the casing bottom secured removably to the casing and having an open 45 top slideway in the inlet compartment, an annular valve seat in said opening and with a flange at, and in engagement with, the inlet compartment side of, the cross-wall, having means associated therewith for releasably drawing it in clamped relation with the cross-wall and adapted upon release of said means and removal of the cap to be removed from the casing through the aforesaid hole, a directional flow controlling wall in rigidly connected relation with the seat 50 disposed normally in the outlet compartment and adapted to direct the fluid through the last mentioned compartment and the adjoining open end of the casing and also to be removed from the casing with the seat, a valve member in the outlet compartment for closing the seat and controlling the flow of fluid from the outlet chamber to the inlet chamber by said flow controlling wall, a valve member carrying plunger slidably mounted in the slideway and adapted to be removed together with the valve member upon removal of the cap, a spring in the slideway disposed between the plunger and the cap and adapted normally to urge the valve member against the seat, and means for shifting the valve member against the force of the spring away from the seat in order to open the seat for the passage of fluid therethrough.

HERBERT HANSEN.
